UNITED STATES PATENT OFFICE.

JAMES F. BROWN, OF CUSTER CITY, TEXAS, ASSIGNOR OF TWO-THIRDS TO
FRANKLIN P. WHITESIDE, OF SAME PLACE, AND ALEXANDER S. BEL-
CHER, OF GAINESVILLE, TEXAS.

DEVICE FOR CONVERTING MOTION.

SPECIFICATION forming part of Letters Patent No. 264,511, dated September 19, 1882.

Application filed August 24, 1882. (No model.)

To all whom it may concern:

Be it known that I, JAMES F. BROWN, a citizen of the United States, residing at Custer City, Texas, have invented certain new and useful Improvements in Mechanical Movements, of which the following is a specification, reference being had therein to the accompanying drawings.

My invention has relation to mechanical movements for converting a reciprocating into a rotary motion so as to impart a steady and regular motion to such machinery as windmills and engines, churning and washing machines, as well as to all other motors to which it may be applied; and the novelty consists in the construction of the same, as will be hereinafter more fully described, and particularly pointed out in the claims.

Figure 1 is a top plan view of the movement, and Fig. 2 is a detached view of the three cranks shown in their relative position on the shaft.

A is a solid shaft, provided with journal-bearings *a a*, which may extend far enough through their supports to receive gear wheels or pulleys for imparting motion. This shaft A is provided with sections B B' B², upon which are turned eccentrics, so as to receive the straps *b b' b²*, attached to the rods 1, 2, and 3.

C, C', and C² are the crank-pins, which also form a portion of the solid shaft A, and each is provided with a connecting-rod, 4, 5, and 6. These crank-pins are placed at equal distances on the revolution, so that when one crank is on the dead-center two are off and exerting their best effect.

7, 8, and 9 represent valve-stems working in the guide-bar D, and 10, 11, and 12 are the rods which impart the motion, through the connecting-rods, to the crank-shaft A. 40

It will thus be seen that as long as a reciprocating motion is given the rods 10 11 12 the shaft A will continue to revolve steadily in the direction in which it was first started, and can be as readily started and stopped, as there is 45 no dead-center or point at which the cranks are not in position to respond at once to the prime motor, and the equal distribution of the imparted motion to the shaft A through the medium of the three cranks insures a uniform 50 and regular motion to the driven machinery.

Having thus described my invention, what I claim is—

1. In a device for converting motion, the solid shaft A, having sections B B' B², forming eccentrics, and the crank-pins C, C', and C², all made of a single piece, substantially as set forth. 55

2. In a device for converting motion, the shaft A, sections B B' B², and crank-pins C, 6c C', and C², in combination with the connecting-rods 10 11 12 and eccentric-straps *b b' b²*, substantially as set forth.

In testimony whereof I affix my signature, in presence of two witnesses, this 24th day of 6: August, 1882.

JAMES F. BROWN.
